UNITED STATES PATENT OFFICE.

HERMAN F. WITTE, OF CHICAGO, ILLINOIS, ASSIGNOR TO THE OTIS ELEVATOR COMPANY, OF EAST ORANGE, NEW JERSEY, A CORPORATION OF NEW JERSEY.

VALVE MECHANISM FOR HYDRAULIC ELEVATORS.

SPECIFICATION forming part of Letters Patent No. 700,877, dated May 27, 1902.

Application filed September 5, 1899. Serial No. 729,433. (No model.)

To all whom it may concern:

Be it known that I, HERMAN F. WITTE, a citizen of the United States, residing at Chicago, in the county of Cook and State of Illinois, 5 have invented a new and useful Valve Mechanism for Hydraulic Elevators, of which the following is a specification.

This invention relates to valve mechanism for hydraulic elevators.

10 The object of the invention is to provide a construction and arrangement wherein the pilot-valve, through which the main valve and the power-valve which actuates it are controlled, is subjected to the action of a low head or pressure.

15 A further object of the invention is to provide means whereby the pressure controlled by the pilot-valve is independent of the pressure of fluid-supply to the machine.

20 A further object of the invention is to relieve the pilot-valve of undue wear resulting from a high-pressure power to be controlled thereby.

25 Other objects of the invention will appear more fully hereinafter.

The invention consists, substantially, in the construction, combination, location, and arrangement, all as will be more fully herein-after set forth, as shown in the accompanying drawings, and finally specifically pointed out in the appended claims.

30 Referring to the accompanying drawings, and to the various views and reference-signs appearing thereon, Figure 1 is a view in side elevation, showing the arrangement of a hydraulic-elevator hoisting apparatus and the application of the invention thereto. Fig. 2 is an end elevation of the valve devices for controlling the hoisting mechanism. Fig. 3 35 is an enlarged view, in central longitudinal section, of the valve mechanism, parts being shown in side elevation and embodying the principles of the invention.

40 The same part is designated by the same reference-sign wherever it occurs.

45 Heretofore in the operation of valve mechanisms for hydraulic elevators it has been the usual custom to operate the power-piston, through which the movements of the main or 50 reversing valve are effected, by the same head

or pressure of fluid-supply employed for effecting the movements of the car—that is, the same head or pressure of fluid supplied to the machine—and consequently the pilot-valve employed in connection with the valve mechanism has been required to control this high pressure, with the result that by reason of the smallness of the pilot-valve leakage quickly develops through wear of the packing thereof under the action of the high pressure of the 60 fluid-supply, which said valve is required to control and to which it is subjected. It is difficult to efficiently pack the pilot-valve, by reason of the smallness of its size, to resist the effects of the high pressure and to prevent leak- 65 age and at the same time to permit the proper adjustments to be made. This has proven to be a defect in practice which it is exceedingly desirable to avoid and overcome, and it is the special purpose of the present invention to pro- 70 vide a construction and arrangement of valve mechanism wherein the pilot-valve is relieved of the high pressure which is supplied to the hoisting-motor and is operated with a low pressure, thus avoiding impairment of the effi- 75 ciency of the packing of said valve, and hence avoiding objectionable leakage. The pressure-supply, through which the power-piston for actuating the main or reversing valve is operated, and hence the pressure which the 80 pilot-valve is required to control, may be de- 85 rived from any suitable or convenient source in the application of the principles of my invention. For instance, this pressure or supply may be derived from an ordinary house- 90 tank or from the usual city water-supply, or it may be taken from the operating system of the elevator hoisting mechanism, but at a reduced pressure, or this pressure may be derived from any other suitable or convenient 95 source, the important feature being that a low pressure of fluid-supply is employed for this work, while a high pressure is required for the hoisting-motor.

Referring to the accompanying drawings, 95 illustrating an operative construction and arrangement for carrying out the principles above outlined, reference-sign A designates a car; B, the main cylinder, to the plunger of which the car is suitably connected; C, the 100

12
automatic stop-valve; D, the accumulator, and E the discharge-tank. These parts may be of the usual or any well-known, suitable, or convenient type of hydraulic-elevator mechanism, and the particular construction and arrangement thereof require no special description.

Reference-sign F designates the pipe which is connected to the discharge side of the main pump, through which the required pressure of operating fluid for the hoisting-motor is secured, and G designates the pipe connecting to the opposite side of the pump. These pipes are ordinarily known as the "pump discharge" and the "pump suction" pipes. The pipe F delivers into the main reversing-valve H, as clearly shown in Figs. 1 and 3. The fluid after passing through the reversing-valve enters pipe J from such valve and then, 10 passing through the automatic stop-valve C and pipe K, finally delivers into the main cylinder B. The exhaust from the main cylinder B passes back through pipe K, automatic stop C, pipe J to the reversing-valve H, thence 15 through pipe L into the discharge-tank E and thence through pipe M to the pump suction-pipe G, thus completing the system.

Now in carrying out the principles of my invention instead of operating the power-piston, through which the main reversing-valve is actuated, by pressure drawn from the pump discharge-pipe F and then returning or discharging such pressure after it has accomplished its purpose of actuating said power-piston back into the pump suction-pipe G, as has heretofore been the usual custom, I supply an operating medium to actuate said power-valve at a low pressure from some other suitable or convenient source, as above 30 explained. For instance, and by way of illustration, the supply of operating fluid for the power-cylinder may be drawn from the pump suction-pipe G through a suitable connection N, and the discharge from said power-cylinder is effected through a pipe O into a suitably and conveniently arranged tank P. The supply of operating fluid through pipe N to the power-cylinder Q is controlled by the pilot-valve R, and the discharge from the 35 power-cylinder Q is effected through the pipes S T, respectively, communicating with the ends of said power-cylinder, said pipes S and T finally joining and delivering into pipe O and thence into tank P.

55 The operation is as follows: When the pilot-valve R is actuated in the usual or any convenient manner from the car in a direction to open the supply-pipe N to one or the other—say the right-hand—end of the power-cylinder Q, the operating medium under low pressure is admitted to the right-hand end of the power-cylinder and causes the power-piston W to move toward the left-hand end of said cylinder, the same movement of the pilot-valve which admits the low-pressure medium to the right-hand end of the cylinder also uncovering the exhaust-port at the left-

hand end of said cylinder, thus permitting the cylinder at the left-hand end to exhaust through pipe S. The movement of piston W toward the left-hand end of the power-cylinder effects a coincident movement of the main reversing-valve H through any suitable connections, thus opening communication between the machine supply-pipe J and the discharge-pipe L. This action opens the main cylinder B to the discharge, and the operating medium is exhausted from said main cylinder B, through pipe K, automatic stop-valve C, pipe J, discharge-pipe L, into discharge-tank E. The exhaust of the main cylinder B is effected by the over weight of the car A, said exhaust resulting in the lowering of the car. Similarly, when the pilot-valve R is moved in the opposite direction, 80 so as to open supply-pipe N to the left-hand end of the power-cylinder Q, the right-hand end of said cylinder is opened to exhaust through pipe T, and thence through pipe O into tank P. At the same time the power-piston W is moved toward the right-hand end of the power-cylinder, and through its connection with the main reversing-valve H said valve is moved to open communication between pipe F and pipe J. Thereupon the 85 operating medium from the pump-discharge is admitted through pipe F, through the reversing-valve H to the machine supply-pipe J, thence through the automatic stop-valve C, pipe K, and into cylinder B, thereby effecting the raising of the car.

The pilot-valve may be actuated in any suitable manner from the car. In the particular form shown, to which, however, the invention is not limited, an arm A' is provided and adapted to be rocked from the car—as, for instance, by being mounted on a rock-shaft B', which may be rotated from the car through the hand-cable or other suitable connections in a well-understood manner, as indicated in dotted lines in Fig. 3. The arm A' is connected by means of a link C' to a pivoted yoke D', to which is pivotally connected the stem E' of the pilot-valve. The particular form of connection between the piston W and the reversing-valve H is unimportant so far as the present invention is concerned. In the particular form shown, to which the invention is not limited, the stem F' of said piston is connected to the tubular valve-stem G' of the reversing-valve through arms H', whereby said valve-stems are connected to move coincidentally and in unison, and, if desired, the yoke D' may be pivotally connected to one of the arms H', thus tending to restore the pilot-valve to its cut-off position when the power-piston W and reversing-valve H approach the limits of their movement in either direction. However, the particular construction and arrangement of devices for actuating the pilot-valve and for securing coincident and simultaneous travel of the power-piston W and reversing-valve H form no part of the present invention and may be varied, al-

tered, or changed, as may be desired, without affecting the scope of my invention. Similarly the construction and arrangement of the hoisting-cylinder B and accumulator D may be of the usual or any ordinary type and connected up in the usual manner, the accumulator D being connected through pipe J' to the supply-pipe F.

From the foregoing description it will be seen that in the particular form shown, to which, however, the invention is not limited, the medium for operating the power-piston W is taken from the pump suction-pipe G, and the pressure of which may be from fifty to two hundred pounds per square inch, whereas the pressure of the operating medium, which passes through the main or reversing valve H, is usually about seven hundred and fifty pounds per square inch. It will also be seen that in the construction and arrangement shown and described the power-cylinder Q discharges into a tank P. In order that the fluid employed for actuating the power-piston may not be wasted, the medium delivered into tank P may be returned into the circulating system, if desired, and in any suitable manner, as by means of an injector or other suitable arrangement. In the particular form shown an auxiliary pump K' is employed for discharging from the tank P through pipes L' and M' into pipe L, which discharges into discharge-tank E of the system. It is obvious, however, that instead of drawing the supply of operating medium for the power-piston W from the circulating system of the apparatus it may be drawn from any other source, as from a separate tank suitably supplied or from the city water system, and in any event the discharge of such power-piston operating medium may be permitted to go to waste, if desired. It is also evident that the principles of my invention may be applied where the operating medium is steam, the essential feature being that the operating medium for the power-piston and which is under the control of the pilot-valve is of large volume and comparatively low pressure, while the medium which actuates the hoisting-motor is of comparatively small volume and large or high pressure.

I have found in the practical operation of my invention, wherein the pilot-valve is required to control a low pressure, that leakage is avoided and that said pilot-valve is more easily actuated and the car responds more quickly and uniformly to the operation of the hand-lever or control-cable on the car.

Many variations and changes in the details of construction and arrangement would readily suggest themselves to persons skilled in the art and still fall within the spirit and scope of my invention. I do not desire, therefore, to be limited or restricted to the particular form of construction and arrangement of devices shown and described. It is also obvious that the associated operating parts may be varied, altered, and changed in

the details of their construction and arrangement without affecting the principles of my invention; but,

70

Having now set forth the object and nature of my invention and an operative embodiment of the principles thereof, what I claim as new and useful and of my own invention, and desire to secure by Letters Patent of the 75 United States, is—

1. In a hydraulic-elevator hoisting mechanism, a hoisting-cylinder, a reversing-valve for controlling the supply to and exhaust from said cylinder of an operating medium 80 at high pressure, a discharge-tank for said hoisting-cylinder, a power-cylinder, a piston arranged therein and connected to said reversing-valve for actuating the latter, pipes delivering from said discharge-tank into both 85 ends of said power-cylinder, whereby an operating medium at low pressure is delivered into either end of said power-cylinder to operate said piston in both directions, a pilot-valve for controlling said pipes, and means 90 for returning the exhaust from said power-cylinder into said discharge-tank, as and for the purpose set forth:

2. In a hydraulic-elevator hoisting mechanism, a circulating system for a high-pressure operating medium, a main or reversing 95 valve for controlling said system, a power-cylinder, a piston operating therein, a low-pressure hydraulic supply, pipes delivering from said supply into said power-cylinder, a 100 pilot-valve arranged to control the admission of said low-pressure medium to either end of said power-cylinder at will, to operate said piston in either direction, and means whereby the discharge of such low-pressure operating medium is returned into the circulating 105 system, as and for the purpose set forth.

3. In a hydraulic-elevator hoisting mechanism, a circulating system for a high-pressure operating medium, a main or reversing 110 valve for controlling said system, a power-cylinder, a piston operating therein, a low-pressure hydraulic supply, pipes delivering from said supply into said power-cylinder, a pilot-valve arranged to control the admission of 115 said low-pressure medium to either end of said power-cylinder, manually-operated means for moving said pilot-valve in either direction to open either end at will of said power-cylinder to the source of low-pressure supply 120 to operate said piston in either direction, connections between said piston and said reversing-valve, and means actuated by the movement of said reversing-valve for moving said pilot-valve to close communication with the 125 source of low-pressure supply of said cylinder and to open said cylinder to exhaust, as and for the purpose set forth.

4. In a valve mechanism for elevators, a main reversing-valve arranged to control the 130 supply of high-pressure, operating medium to and from the hoisting-motor, in combination with a cylinder, a piston arranged there-in and connected to said reversing-valve for

operating the latter, a valve-chest, a low-pressure hydraulic supply, pipes delivering from said supply to said chest, an exhaust-pipe also communicating with said chest, ports arranged to open communication between said chest and each end of said cylinder, a pilot-valve for controlling said ports, manually-operated devices for moving said valve to open said ports, and means operated by the movement of said piston for automatically moving said pilot-valve to close said ports and to open said cylinder-exhaust, as and for the purpose set forth.

5. In a valve mechanism for hydraulic elevators, a hoisting mechanism, a main or reversing valve arranged to control the supply of high-pressure, operating medium to and from the hoist-motor, a power-piston for operating said valve, a cylinder in which said 10 piston operates, a source of low-pressure hydraulic supply for said power-cylinder, ports arranged to deliver into each end of said power-cylinder and to each side of said piston, a pilot-valve for controlling said ports, 15 manually-actuated devices for moving said pilot-valve in either direction to open either end of said power-cylinder to the source of low-pressure supply, and means actuated by the movements of said piston for moving said 20 pilot-valve to close said cylinder to the source 25

of low-pressure supply and to open the same to exhaust, as and for the purpose set forth.

6. In a valve mechanism for elevators, a main valve arranged to control the supply and discharge of a high-pressure operating medium to and from the hoisting-motor, in combination with a cylinder, a piston operating therein, connections between said piston and main valve for operating the latter, a pilot-valve, ports controlled by said pilot-valve, said ports leading to a different and independent source of supply from that of the hoisting-motor, means for manually moving said pilot-valve in either direction at will to open said cylinder to its independent source 30 of supply, and means actuated by the movements of said piston when said pilot-valve is moved in either direction for automatically moving said pilot-valve in the opposite direction to close said cylinder to its source of supply and to open the same to exhaust, as and for the purpose set forth.

In witness whereof I have hereunto set my hand, this 30th day of August, 1899, in the presence of the subscribing witnesses.

HERMAN F. WITTE.
